UNITED STATES PATENT OFFICE.

SAMUEL H. HARRINGTON, OF NEW YORK, N. Y.

TOOL FOR BONDING RAILS.

SPECIFICATION forming part of Letters Patent No. 723,270, dated March 24, 1903.

Application filed June 15, 1901. Serial No. 64,745. (No model.)

To all whom it may concern:

Be it known that I, SAMUEL H. HARRINGTON, a citizen of the United States, residing at New York city, county of New York, State 5 of New York, have invented a certain new and useful Improvement in Tools for Bonding Rails; and I declare the following to be a full, clear, and exact description of the invention, such as will enable others skilled in the 10 art to which it pertains to make and use the same, reference being had to the accompanying drawings, which form a part of this specification.

My invention relates to implements for 15 bonding rails, and more particularly to an improved tool especially adapted to secure to a rail a bond of the type shown and described in my application for Letters Patent filed July 3, 1901, Serial No. 66,938.

20 The object of my invention is to provide a device of the character specified which while simple in construction will efficiently secure in place the terminal of a rail-bond.

A further object of my invention is to provide 25 a bonding implement which will in one operation secure a terminal of a bond to a rail and also impress upon such terminal a mark or a character of a predetermined design.

30 The invention will be more fully described hereinafter with reference to the accompanying drawings, in which the same is illustrated as embodied in a convenient and practical form, and in which—

35 Figure 1 is a view of the tool in elevation and of the extension-piece for using the same in longitudinal section; Fig. 2, a view similar to Fig. 1, the section of the extension-piece being at a right angle to that of Fig. 1; 40 Fig. 3, an end elevation of the tool and extension-piece; Fig. 4, a side elevation of a modified form of my invention; Fig. 5, an end view of the modification shown in Fig. 4, and Fig. 6 a perspective view of a key of common construction.

45 Similar reference characters are used to indicate similar parts in the several views of the drawings.

The improved tool consists, essentially, of 50 a body portion comprising annular enlargements separated by an annular recess and a

shank portion to which power is applied in using the device.

Reference-letter A, referring particularly to Figs. 1, 2, and 3, indicates the tool, consisting of the shank portion *a* and the annular enlargements *e* and *g*. *f* indicates an annular recess separating the annular enlargements or projections. The annular projection *e* is preferably made slightly smaller in 60 diameter than the annular projection *g* for a purpose to be hereinafter described. The shank *a* is preferably tapered to conform to the Morse standard in order that it may be readily removed from the stock or extension-piece B. The shank *a* is provided with a reduced end adapted to fit in a recess connecting the socket *b*' and the opening *b* in the stock B. The extension-piece or stock B is provided with a socket *b*', preferably of a 65 shape to conform to the shank *a*. Extending transversely through the stock B is an opening *b*, into which projects the reduced end of the shank *a*. Any suitable device—such, for instance, as the key C—may be inserted in 70 the opening *b* to disengage the tool A from the stock B by a wedging action between the reduced end of the shank *a* and the opposite wall of the opening *b*. The end of the stock B surrounding the socket *b*' is provided with 75 a die D, containing letters, figures, or other characteristic marks.

The operation of the embodiment of my invention shown in Figs. 1, 2, and 3 is as follows: The tubular terminal of a rail-bond having been inserted in an aperture through the rail, the end of the tool on which is formed the annular enlargement *e* is placed in the tubular opening of the terminal and power is applied to the end of the extension-piece B. 80 The annular enlargement *e* is forced through the tubular terminal of the rail-bond, and thereby slightly enlarges the same. The annular recess *f* then passes through the tubular terminal without engaging the wall thereof, 85 such annular recess being preferably of a width slightly greater than the width of the bond-terminal. The annular projection *g* being greater than the enlargement *e* expands the tubular bond terminal to a greater degree, 90 and thereby firmly secures it within the aperture in the rail. When the enlargement *g* 95

passes through the tubular terminal, the end of the extension-piece forcibly engages the face of the tubular bond-terminal and impresses thereon the letter, figure, or other characteristic mark formed on the die D. The tool may then be removed from the stock by inserting the key C.

In the modified form of my invention shown in Figs. 4 and 5, A' indicates the tool the shank portion a' of which is adapted to directly receive the blow or pressure necessary to force the tool through the bond-terminal. In this form of my invention, therefore, the use of the stock or extension-piece is unnecessary. The annular enlargement e' is provided with radial ribs D' of any desired number. The annular enlargement g' is provided with similar ribs D², also of any number desired. f' indicates the annular recess between the annular enlargements e' g', such enlargements being preferably of unequal size, the former being slightly less in diameter than the latter.

The operation of the embodiment of my invention shown in Figs. 4 and 5 is similar to that previously described with reference to Figs. 1, 2, and 3, except that no stock or extension-piece is used, the tool being forced through the terminal by power applied directly to the shank a'. The ribs D' and D² form grooves or other characteristic marks within the tubular terminal of the rail-bond.

From the foregoing description it is evident that I provide a tool capable of expanding a bond-terminal within an aperture in a rail and at the same time impressing on each terminal a characteristic mark indicating that the terminal has been properly expanded in place and also indicating other information that may be desired—such, for instance, as by whom the bond was applied and at what date. By forming the annular projections of different sizes the bond-terminal is slightly expanded by the passage therethrough of the first enlargement on the end of the tool and is subsequently expanded to a greater degree by the passage therethrough of the second enlargement, the result being that the terminal is secured in place by the requisite expansion without being drawn through the aperture in the rail, as would be the case if a continuous engagement took place between the tool and the terminal throughout the entire passage of the former through the latter.

While I have described more or less precisely the details of construction, I do not wish to be understood as limiting myself thereto, as I contemplate changes in form, the proportion of parts, and a substitution of equivalents as circumstances may suggest or render expedient without departing from the spirit of my invention.

What I claim as my invention is—

65 1. A tool for bonding rail-joints, comprising a body portion, an annular enlargement thereon, and a second annular enlargement

separated from the first by an annular recess, said enlargements adapted to successively pass through and thereby expand a bond-terminal within an opening through a rail.

2. A tool for bonding rail-joints, comprising a body portion, one end of which is curved in longitudinal section, an annular projecting portion, separated from the said end by 75 an annular recess, said curved end and projecting portion adapted to successively pass through and thereby expand a bond-terminal within an opening through a rail.

3. A tool for bonding rail-joints, comprising a body portion, an annular projecting portion separated from one end of the body portion by an annular recess, said annular projecting portion being curved in longitudinal section, and adapted to pass through and 85 thereby expand a bond-terminal within an opening through a rail.

4. In a tool for bonding rail-joints, the combination with a body portion having an annular recess of a width greater than the thickness of the web of a rail, of annular projecting portions at either side of the annular recess adapted to expand a bond-terminal within an opening through the rail-web, and a shank of smaller cross-section than said annular projecting portions, whereby the tool may pass entirely through the web of the rail, 95 substantially as described.

5. In a tool for bonding rail-joints, the combination with a body portion having an annular recess, of annular projecting portions at either side of said annular recess adapted to expand a bond-terminal within an opening in a rail, and means for impressing upon the bond-terminal a characteristic mark during 105 the operation of expanding the same, substantially as described.

6. In a tool for bonding rails, the combination with a body portion having an annular recess, of annular projections on either side of 110 said recess, a shank of smaller cross-section than said annular projections, and an extension-piece having a socket adapted to receive said shank, substantially as described.

7. The combination with a tool comprising 115 an enlarged portion and a reduced shank portion, and adapted to pass entirely through a bond-terminal and thereby expand the same within an opening in a rail, of an extension-piece having a socket to receive said shank 120 portion, and having a die on its end surrounding said socket, substantially as described.

8. The combination with a tool for expanding a bond-terminal within an opening in a 125 rail comprising a series of annular enlargements of graduated diameter, of an extension-piece adapted to force said tool entirely through the bond-terminal, said extension-piece having a die on its end surrounding the 130 tool adapted to impress a characteristic mark upon the bond-terminal when the tool passes therethrough.

9. In a tool for bonding rails, the combina-

tion with a body portion having an annular recess, of annular projections on either side of said recess adapted to expand a bond-terminal within an opening in a rail, a shank of 5 smaller cross-section than said annular projections, and an extension-piece having a socket to receive said shank and having a die on its end whereby a characteristic mark is impressed upon the bond-terminal, substantially as described.

10. A tool for bonding rail-joints comprising

ing a series of annular enlargements of graduated diameters, said enlargements adapted to successively pass through and thereby expand the bond-terminal within an opening in 15 a rail.

In testimony whereof I sign this specification in the presence of two witnesses.

SAMUEL H. HARRINGTON.
